UNITED STATES PATENT OFFICE

170,452

SPRAY HEAD FOR AEROSOL BOMBS AND THE LIKE

Leonard B. Drell, Glencoe, Ill.

Application May 4, 1953, Serial No. 24,830

Term of patent 14 years

(Cl. D62—2)

To all whom it may concern:

Be it known that I, Leonard B. Drell, a citizen of the United States, residing at Glencoe, in the county of Cook and State of Illinois, have invented a new, original, and ornamental Design for a Spray Head for Aerosol Bombs and the like, of which the following is a specification, reference being had to the accompanying drawing, forming part hereof.

Fig. 1 is a perspective view of a spray head for aerosol bombs and the like, showing my new design;

Fig. 2 is a front elevational view thereof;

Fig. 3 is a rear elevational view thereof;

Fig. 4 is a top plan view thereof;
Fig. 5 is a side elevational view thereof; and
Fig. 6 is a bottom plan view thereof.

I claim:

The ornamental design for a spray head for aerosol bombs and the like, substantially as shown.

LEONARD B. DRELL.
